UNITED STATES PATENT OFFICE

170,311

UTILITY STOOL

Donald W. Doherty, Crystal Lake, Ill., assignor to
Queen Manufacturing Co., Inc., Chicago, Ill.,
a corporation of Illinois

Application March 18, 1953, Serial No. 24,095

Term of patent 14 years

(Cl. D15—8)

To all whom it may concern:

Be it known that I, Donald W. Doherty, a citizen of the United States, residing at Crystal Lake, in the county of McHenry, in the State of Illinois, have invented a new, original, and ornamental Design for a Utility Stool, of which the following is a specification, reference being had to the accompanying drawing, forming a part hereof.

Figure 1 is a perspective view of a utility stool, showing my new design;

Figure 2 is a side elevational view of the utility stool.

I claim:

The ornamental design for a utility stool, as shown.

DONALD W. DOHERTY.
